CLAIM

The ornamental design for a touchpanel as shown and described.

DESCRIPTION

FIG. 1 is a bottom rear perspective view of a touchpanel according to the present invention.

FIG. 2 is a bottom top perspective view of the touchpanel of FIG. 1.

FIG. 3 is a front view of the touchpanel of FIG. 1.

FIG. 4 is a rear view of the touchpanel of FIG. 1.

FIG. 5 is a left side view of the touchpanel of FIG. 1.

FIG. 6 is a right side view of the touchpanel of FIG. 1.

FIG. 7 is a top view of the touchpanel of FIG. 1.

FIG. 8 is a bottom view of the touchpanel of FIG. 1; and, FIG. 9 is an enlarged corner view of the touchpanel of FIG. 1.

The dash-dot broken line seen in FIG. 9 depicts the extents of the enlarged partial view and forms no part of the claim; while the dash-dash broken lines in the drawings depict unclaimed environmental structure only and form no part of the claimed design.

1 Claim, 9 Drawing Sheets(56)
